W. MALLIER,

LOCK.

N° 14,616.

Patented Apr. 8, 1856.

UNITED STATES PATENT OFFICE.

WILLIAM MAURER, OF NEW YORK, N. Y.

LOCK.

Specification of Letters Patent No. 14,616, dated April 8, 1856.

To all whom it may concern:

Be it known that I, WILLIAM MAURER, of the city, county, and State of New York, have invented a new and Improved Lock 5 for Safes, Bank, Vault, and other Doors; and I do hereby declare that the following is a full, clear, and exact description of the same, reference being had to the annexed drawings, making a part of this specification, in which—

Figures 1, and 2, are side views of the tumblers of my improved lock. Fig. 3, is a view of the bolt. Fig. 4, is a transverse vertical section of the lock. Fig. 5, is a detached perspective view of the lever or crank by which the bit is turned. Fig. 6, is a detached perspective view of the bit. Figs. 7 and 8, are detached views of the lever by which the bolt catch is operated. Figs. 9, 15 10 and 11, are detached views of the bolt catch. Figs. 12, and 13 are interior views 20 of the lock. Fig. 14, is a detached view of the key.

Similar letters of reference indicate corresponding parts in the several figures.

This invention relates to a new and improved lock for safes, bank vault and other doors.

The invention consists in the peculiar 30 construction and arrangement of a series of tumblers, a bolt catch and bit, as will be presently fully shown and described.

A, Figs. 4, 12 and 13, represents the casing of the lock, constructed of metal, and B, 35 represents a series of tumblers, any proper number being used, said tumblers working on a common pin or rod *a*, at the lower part of the casing. The tumblers B, are in the form of frames or they may be described as 40 having their centers cut out and a bit C, is fitted and works within them, the shaft *b*, of the bit having its bearings in the front and back plates of the casing A. The lower parts of the tumblers B, just below the bit 45 C, have curved slots *e*, made through them, one slot through each tumbler. The slots are all of the same form and size. Each tumbler has a spring *d*, attached to it, the outer ends of the springs bearing against 50 the sides of the casing, the spring of every alternate tumbler bearing against one side of the casing and the springs of the intermediate tumblers against the opposite side, as shown in Figs. 12 and 13. By this arrangement, one half of the tumblers are 55 thrown in an opposite position to the others

and the slots *c*, are consequently thrown out of line with each other. This will be understood by referring to Figs. 12 and 13. The upper edges of the tumblers have each a slot *e*, cut in them, said slots being of elbow or right angular form, the upper ends of the slots extending to the edges of the tumblers; the slots in every alternate tumbler are in a reverse position to those in the intermediate tumblers as shown in Figs. 1 and 60 2, and these slots are made of varying lengths.

D, represents the bolt which is fitted in the upper part of the casing A. The bolt 70 D, has an elbow or right angular slot *f*, made in its under side, as shown in Figs. 3, 12, and 13.

E, is a bolt catch, which fits in the upright portion of the slot *f*, in the bolt, and free 75 from the slots in the tumblers, when the lock is in a locked state, as shown in Fig. 12. The catch being free or out of the upright portion of the slot *f*, and within the slots *e*, in the tumblers when the lock is in an un- 80 locked state, see Fig. 3. The catch E, has a spring *g*, bearing against it, as shown clearly in Figs. 12 and 13.

F, is a lever or arm, which works on a pin *h*, within the casing A. The outer end 85 of this lever is directly underneath the catch E.

The operation will be readily understood. Suppose the lock to be in a locked state, as shown in Fig. 12. To unlock the lock, the 90 catch E, must pass out of the upright portion of the slot *f*, in the bolt and into or through the upright portions of the slots *e*, in the tumblers B, and, of course the upright portions of the tumbler slots must be 95 brought in line with each other. To effect this, the tumblers B, are moved by turning the bit C, by means of a crank or lever A' on the outer end of the shaft *b*, the tumblers being moved till the slots *c*, are in line, so 100 that a key B', may be inserted in them, said key having recesses or slots *a'*, of varying length in its edges or sides, as shown in Fig. 14. When the key is inserted, the hand is taken from the crank or lever and the 105 springs *d*, of the tumblers will throw the tumblers in such positions, that the upright portions of the slots *e*, will be in line, as the slots or recesses *a'*, in the key, are so made as to cause the slots *e*, in the several tumblers to assume the proper position. When 110 the upright portions of the slots *e*, are in

line, the catch E, is thrown free from the upright portion of the slot f, in the bolt and into the slots e, in the tumblers, by the spring g, as shown in Fig. 13, and the lock 5 is unlocked.

The lock is locked by merely turning the bit C, from right to left as indicated by the arrow, Fig. 13, the bit acting upon the arm or lever F, and causing it to throw the catch 10 into the upright portion of the slot f, in the bolt when the upright portions of the slots e, come in line. When the key B', is withdrawn, the tumblers B, must be previously brought in line by turning the bit C.

15 The above lock is extremely simple, not liable to get out of repair, may be cheaply

constructed, and is burglar and powder proof.

Having thus described my invention, what I claim as new and desire to secure by Letters Patent, is,

The tumblers B, having slots c, e, made in them, as shown, in combination with the slotted bolt D, bolt catch E, arm or lever F, and bit C, the above parts being arranged 25 as shown and described for the purpose specified.

WILLIAM MAURER.
